UNITED STATES PATENT OFFICE.

THOMAS F. DUFF, OF SPOKANE, WASHINGTON.

TYPE-CASTING MACHINE.

Application filed September 18, 1923. Serial No. 663,483.

To all whom it may concern:

Be it known that I, THOMAS F. DUFF, a citizen of the United States, residing at Spokane, in Spokane County and State of Washington, have invented certain new and useful Improvements in Type-Casting Machines, of which the following is a specification.

The present invention relates to improvements in type casting machines and particularly to the structure involving the discharging means for molten metal from the melting pot.

As is well known in the art, because of the intense heat from the molten metal to which the mouth piece or discharge portion of the melting pot is subjected, difficulty is encountered when it becomes necessary to remove the locking key or bar preparatory to the removal of the die and die plate in the discharge head of the melting pot. The locking keys now in use become wedged in place with such frictional contact that the keys, die members and sometimes the guideways formed on the discharge head of the pot are broken by blows in an attempt to remove the key, thus rendering useless the broken parts and in the case of the pots incurring considerable expense because of waste. With the keys now in use the area of frictional contact between the key, guideway and die extends throughout the entire length of the key thus effecting a maximum and excessive area of frictional contact with the resulting great difficulty in dislodging the key. By the utilization of my invention I provide a locking key applicable to machines now in use and adapted for manufacture with the standard types of machines, which key has a minimum but effective area of frictional contact when in locked position, and which requires but slight effort to disengage the contacting parts and to dislodge the key. The results attained with this invention overcome the difficulties encountered with keys now in use and wear and tear upon the parts affected are avoided.

With the above ends in view the invention consists in certain novel features of construction and combinations and arrangements of parts as will be hereinafter set forth and claimed.

In the accompanying drawings I have illustrated one complete example of the physical embodiment of my invention wherein

the parts are combined and arranged in accordance with the best mode I have thus far devised for the practical application of the principles of my invention.

Figure 1 is a sectional view of so much of a standard form of melting pot as is necessary to illustrate the adaptation thereto of my invention.

Figure 2 is an enlarged sectional detail view of the discharge head of the melting pot showing the combination therewith of the device of my invention.

Figure 3 is a face view showing the discharge head, the die and the locking key in locked position.

Figure 4 is a perspective view of the die plate in the discharge head, detached.

Figure 5 is a transverse sectional view of the die plate at line 5-5 of Figure 4.

Figure 6 is a perspective view of the locking key of my invention. The numeral 1 indicates the melting pot of standard construction and designed to oscillate on its pivot 2 as usual. The molten metal for use in the casting machine is forced by the plunger 3 up through the discharge spout or passage 4, and the device of my invention is adapted for use in connection with the discharge head 5 of the pot at the end of this spout or passage 4.

Within the discharge head and extending across the head is an inset socket 6 as usual in which the well known form of die plate 7 is seated, and the plate has the usual longitudinal groove 8 and transverse openings 9 for the passage therethrough of the molten metal from the melting pot. In the face of the discharge head is provided an enlarged groove 10 having an upper undercut longitudinal lip 11 with its inner wall at an inclination of approximately 30° and the lower, undercut lip 12 in the head has its inner face at an approximate angle of 45°.

The die is designated by the numeral 13 and is fashioned with the usual upper angular face 14 complementary to the lip 11 and a complementary lower angular face 15 complementary to the key as will be described. Openings 16 extend transversely through the die, which is seated in the grooved face of the head and these openings register with the openings 9 of the die plate for passage of molten metal.

The die and its die plate are locked in the sockets and grooves provided therefor by

the utilization of the locking key 17 which is a metal bar with outer and inner plane parallel faces, but provided with an upper angular face 18 complementary to the face 15 of the die, and a lower angular face 19 complementary to the face of the lip 12 of the head. Along its lower edge the locking key is provided with a series of spaced projecting lugs 20, and the lip 12 of the head is fashioned with spaced complementary notches 21. These notches may be fashioned in the lip during the manufacture of the machine, or they may be milled by the use of suitable tools in the lips of existing machines in which case the customary keys are dispensed with and the key illustrated in Figure 6 is utilized.

After the die plate and the die 13 are placed in position, the key is slipped in from one side of the head and forced along beneath the die, with its upper angular face 18 in contact with the lower face of the die, and its lower lugs 20 riding over the face of lip 12. The end of the key, designated 20' is slid through the space provided therefor and this end projects slightly, after the key is in place as indicated in Fig. 3. In this position the lugs 20 are offset slightly from the notches 21 and rest upon the face of the lip 12 in such manner as to securely hold the key, die and its die-plate in rigid position. When it becomes necessary to remove the die, the key is first loosened by a tap on the end 20' which results in moving the key to the right in Fig. 3 sufficiently to permit the lugs 20 to drop into the notches 21 provided therefor, and this dropping of the key relieves the die from pressure and it may therefore be removed as usual. It will be apparent that a minimum of frictional contact is provided between the lugs and the lip 12 and this frictional contact may be overcome with facility to insure the necessary, but slight, longitudinal movement of the key for removal of the die. After the die has been replaced or a new one applied, the key may again be lifted and restored to locked position for effectively holding the die in position for use.

Having thus fully described my invention, what I claim as new and desire to secure by Letters Patent is—

1. In a machine as described, the combination with a grooved discharge head and a die therein, of a locking key having frictional contact with said die, and spaced frictional devices on said key for contact with said grooved head.
2. In a machine as described, the combination with a grooved head having a lower lip and spaced notches therein, and a die in said grooved head, of a locking key having frictional contact with said die, and spaced frictional lugs on said key for contact with said lower lip, and adapted to seat in said notches when the key is loosened.
3. In a machine as described, the combination with a discharge head having a groove therein and undercut upper and lower lips to said groove, of a die in said groove having dovetail edges, a locking key having dovetail edges and adapted for frictional contact with the die, spaced frictional lugs on said key for contact with said lower lip, and notches in said lower lip to receive said lugs.
4. The combination of a discharge head having a recessed groove and a die-plate and die therein, and a locking key having frictional contact with said die and spaced frictional devices on said key for contact with said grooved head.

In testimony whereof I affix my signature.

THOMAS F. DUFF.
